UNITED STATES PATENT OFFICE

2,098,506

BUFFING MACHINE

George E. McLaughlin, Salem, and Winn E. Broughton, Peabody, Mass., assignors to The Turner Tanning Machinery Company, Portland, Maine, a corporation of Maine

Original application June 5, 1936, Serial No. 83,718. Divided and this application January 12, 1937, Serial No. 120,286

8 Claims. (Cl. 51—78)

This invention relates to machines for operating upon hides, skins and leather. While the invention is illustrated with reference to a machine for buffing leather surfaces it will be understood that the invention and various important features thereof may have other applications and uses.

This application is a division of a co-pending application Serial No. 83,718, filed June 5, 1936, in the names of George E. McLaughlin and Winn E. Broughton.

It is an object of the invention to improve various features of buffing machines and particularly to facilitate presentation of pieces of work to the buffing roll. It is a further object of the invention to provide improved means for preventing work pieces from being drawn into suction means provided to remove dust produced by the buffing operation, and at the same time to facilitate the removal of dust from the buffing roll.

To these ends, and in accordance with an important feature of the invention, there is provided a work supporting roll movable toward and from a buffing roll in an organization wherein the work supporting roll is driven by means controlled by a treadle mechanism so arranged that the driving means for the roll becomes operative to effect rotation of the latter just before the roll presents the work piece to the buffing roll. The purpose of this arrangement is to secure buffing of the surface of a work piece while the latter is moving at a predetermined rate to insure uniformity in the product. Conveniently, the work supporting roll is at the upper end of a member which is pivoted on a horizontal axis about midway of the length of said member, the roll being driven by a chain in engagement with a sprocket wheel connected to the shaft of the roll and also with a sprocket wheel in such relation to the lower end of said member as to permit swinging of the member while the driving chain is in place and in operative relation to its driving means. As shown, the chain is driven by a sprocket on a shaft which carries rotatably mounted thereon a driving pulley adapted to be clutched to the shaft through the operation of a treadle mechanism which also effects movement of the work supporting roll in directions toward and from the buffing roll.

Preferably and as shown, there is provided a brush roll rotatable in contact with the surface of the buffing roll to remove dust from the abrasive covering of the latter and to prevent a work piece from clinging to the buffing roll and from

being drawn into a suction means provided to carry away the dust of the buffing operations. Conveniently, said brush roll has rows of bristles spaced apart in the direction of the circumference of the roll such distances that during rotation of the brush roll an adjacent opening into a suction conduit will be practically unobstructed at regular intervals by said roll, thereby facilitating entrance of dust-laden air into the suction means by which such air is drawn away from the buffing cylinder. If desired the brush roll may be located to brush the surface of a buffed piece of work, a member being provided to back the work piece against the thrust of the brush roll.

These and other important features of the invention and novel combinations of parts will now be described in detail in the specification and then pointed out more particularly in the appended claims.

In the drawing,

Fig. 1 is a view in side elevation, and partly in section, of a buffing machine;

Fig. 2 is a sectional view taken along the line II—II of Fig. 1; and

Fig. 3 is a detail view of a clutch mechanism arranged to be operated by the treadle shown in Fig. 1.

In the illustrated machine, which is specially designed for performing buffing operations upon tanned hides and skins, there are provided work supporting rolls 2 and 4 mounted for rotation in the upper end of a pair of swing arms, one of which is shown at 6 in Fig. 1, the said swing arms being mounted for oscillation upon a shaft 8 carried by the front standard of the machine frame 10. Means is provided under control of a treadle 12 for moving the work supporting rolls 2 and 4 between an open or work receiving position and a work presenting position with respect to a buffing roll 14 and its abrasive sheet covering 15. Enclosing the larger part of the buffing cylinder 14 is a hood member 16 and a larger hood member 17 which together form part of an air suction device represented in general by reference character 18, the purpose of said device being to draw off from the neighborhood of the buffing roll 14 all of the dust-laden air which results from the buffing operations. The suction device by removing the dust helps to keep the abrasive sheet freer from dust than it otherwise would be. Located below the buffing roll or cylinder 14 is a brush roll 20 positioned adjacent to the lower opening into the air suction device to prevent the work piece from being drawn around

the buffing roll 14 and into the air-suction device. This brush roll also cleans the abrasive sheet 15 and thus gives it a longer life.

The buffing roll 14 is preferably of that type 5 wherein the abrasive sheet material 15 is wrapped around the roll and secured thereto by having its ends passed through an inclined slot in the cylindrical wall of the roll and into engagement with clamping means constructed and arranged 10 to maintain the abrasive sheet material properly tensioned upon the cylindrical surface of the roll 14, as fully described in the said copending application.

As stated above, the brush roll 20 operates to 15 prevent wrapping of a piece of work about the buffing cylinder 14, and at the same time insures that the work piece will not be drawn into the suction device 18. As shown, the brush roll 20 has its bristles or brush portions arranged in parallel 20 rows spaced substantial distances from each other so that air may at certain times pass freely into a lower entrance 92 of the air-suction device 18. It is to be understood that this free passage 25 of dust-laden air takes place at intervals during the relatively slow rotation of the brush roll 20, the passage to the entrance 92 being exposed each time that a space between two adjacent rows of bristles reaches a position slightly beyond the 30 position of the roll shown in Fig. 1. Each of the parallel rows of bristles presents a straight blade-like edge surface in wiping down any advancing edge of the work piece which might otherwise hug the abrasive roll and enter the suction system, it being noted in this connection that the roll 20 35 rotates in a direction the same as that of the abrasive or buffing roll 14, as indicated by the arrows in Fig. 1 of the drawing, whereby the upper surface of the brush roll 20 moves in a direction the reverse of the adjacent lower surface of the 40 buffing roll 14. Upon inspection of Fig. 1, it will be observed that the brush roll 20 is of a diameter such as to preclude the possibility of a work piece passing around the lower periphery of the brush roll and into the open end 92 of the air suction 45 device 18. As shown, the diameter of the brush roll is about double the corresponding dimension of the opening 92.

If desired, the brush roll 20 may also be positioned to brush the surface of the work which is 50 undergoing buffing operations. For this purpose the work support, including the swing arms 6, is provided with a plate 94 to back the depending portion of the work piece while the brush roll 20 is operating thereon, it being understood that 55 the brush roll is adjusted to the left in Fig. 1 to the desired position to perform a brushing operation on the work. With this function in mind, the brush roll 20 is mounted upon a pair of arms one of which is shown at 96 mounted rotatably upon a 60 stud 98 carried by a plate 100, the rear of each arm 96 being provided with a slot 102 arcuate with respect to a center at the axis of the stud 98. A second stud 104 secured to plate 100 is located in said slot 102. Upon tightening a nut 106 upon 65 the outer end of the stud 104 the arm 96 is secured in the adjusted position shown in Fig. 1. As clearly indicated in Figs. 1 and 2, the plate 100 is adjustably secured to the frame 10 of the machine by threaded bolts 108 in a slot 110 in the 70 plate 100, proper manipulation of the nuts on said bolts 108 being all that is necessary to permit adjustment of the plate 100 in a horizontal direction toward the front of the machine so that the brush roll 20 may operate upon portions of the work 75 piece while the latter is backed by the plate 94.

When this adjustment of the plate 100 is made, it is also necessary to swing the arms 96 in an upward direction through proper manipulation of the nut 106 on the bolt 104. It will be noticed that the brush roll 20 is rotated counterclockwise to direct the work piece downwardly in a direction away from the buffing roll 14. Since the primary function of the brush roll 20 is to prevent improper displacement of the work piece, the said roll must be adjusted in an upward direction into 10 properly spaced relation with respect to the surface of the buffing roll at the same time that it is made to co-operate with the backing plate 94. If desired, the brush roll 20 may be left in the position shown in Fig. 1 and a separate roll provided for brushing dust from the surface of the work piece in co-operation with the plate 94.

As pointed out above, the work supporting rolls 2 and 4 are movable between an open or work receiving position and a closed or work presenting 20 position with respect to the buffing roll 14. This movement of the work supporting rolls is secured through proper operation of the treadle 12 during which a toggle comprising links 114 and 116 is straightened to the position shown in Fig. 1 to 25 bring the roll 4 into work presenting position relative to the buffing roll 14. As shown, the link 114 is pivoted at 118 to a member 120 which is screw threaded into a part 122 common to the two swing arms 6. Through proper adjustment of the screw 30 threaded member 120, it is possible to vary the distance between the roll 4 and the buffing roll 14 in accordance with variations in the thickness dimensions of different lots of work.

Preferably, and as shown, the work supporting 35 rolls 2 and 4 are positively driven to feed a work piece into the machine for the buffing operation. For this purpose, the shafts of the rolls 2 and 4 have secured thereto sprocket wheels 130, 132, respectively, about which passes a chain driving element 134 which is in engagement with two idler sprockets 136 and 138 carried by the lower end of the front standard of the machine frame 10. This same chain 134 is extended rearwardly to pass around and be driven by a sprocket 140 on 40 a shaft which carries also a gear 142 arranged in mesh with a pinion 144 on a shaft 145 which carries loosely a pulley 146 arranged to be driven continuously by means of a belt 147 from a power shaft 150. For clutching the shaft 145 to the pulley 146 there is provided a clutch mechanism, shown generally at 148 in Fig. 3, which is arranged to be operated by yoke 149 on a bell crank lever 151 connected by a long link 152 to an arm 154 extending up from and rigidly connected to the treadle 12, the said rod 152 passing loosely through an opening in the arm 154 and having on its free end a spring 156, the arrangement being such that, upon depressing a tread portion 158 of the treadle 12, the clutch 148 is thrown in to cause driving of 50 the work supporting rolls 2 and 4 just before the roll 4 reaches work presenting position with respect to the buffing roll 14. Conveniently there are provided work supporting plates 160 and 162 in 55 association with the rolls 2 and 4.

As illustrated, the suction device 18 comprises not only the hood members 16 and 17 but also a conduit 170 which leads to an enclosed blower (not shown). To insure removal of all of the dust-laden air there is provided also a supplementary conduit 172 which leads to an opening at 174 in a sheet metal pocket 176 into which the depending portions of the work piece are received. As shown in Fig. 1, the upper hood member 16 is hinged at 180 so that it may be 60

readily lifted in an upward and rearward direction. The hood member 17 is hinged at 182 so that it also may be turned upwardly and rearwardly to expose the buffing roll 14. The purpose of the hood member 16 is to provide a conduit for drawing away dust-laden air from the front portion of the buffing roll 14 just above the field of operation on the work piece. In spite of the strong current of air which tends to remove all dust from the periphery of the buffing roll 14, some of the air tends to be carried around with the rotating roll, and it is to remove this air that the forward end of the hood member 16 is carried into close relationship with the surface of the buffing roll 14. An adjustable tongue 186 is provided at the forward end of the hood member 16 so that the space between the lower edge of the tongue 186 and the buffing roll may be adjusted, as occasion may require, to secure the best results.

As indicated in a preceding portion of this specification, the slot in the roll 14 is in a plane at an angle to the axis of rotation of the buffing roll, the purpose being to eliminate as much as possible a "bumping" effect that is commonly produced each time that a slot in the cylindrical surface of a buffing roll comes opposite to the work backing portion of a work supporting roll during treatment of a piece of work, it being a well-known fact that there is a noticeable "bumping" effect in the operation of those buffing rolls which are provided with a slot parallel with the axis of rotation of the roll. To insure that uniformity in the treatment of the work which is so desirable, the buffing roll 14 is also constantly reciprocated in an axial direction during its rotation. For this purpose there is provided a forked member 190 (Fig. 1) to engage an end member of the buffing roll 14 fixed to the buffing roll shaft 24. Said forked member 190 is pivotally mounted at 192 intermediate of its ends upon a bracket extending from the frame of the machine. As its other end it is provided with a cam roll 194 arranged to ride upon the surface of a cam 196 on a shaft 198 driven by means of a pulley 200 and a belt 202 from the power shaft 150. It will be readily understood that rotation of the face cam 196 will cause reciprocation of the forked member 190 and hence of the buffing roll 14. For a more complete description of a mechanism for axially reciprocating a buffing roll during rotation of the latter, reference may be had to United States Letters Patent No. 1,377,434, granted May 10, 1921, upon application of L. O. Ramsdell.

In operating the machine shown in the drawing to buff pieces of leather, the operator will introduce a piece of leather upon the work supporting rolls 2 and 4 and will then depress the treadle 12 by stepping on the tread portion 158. Depression of the treadle causes movement of the work supporting rolls 2 and 4 to work presenting position with respect to the buffing roll 14, the treadle, when thus depressed, also initiating drive of the rolls 2 and 4 by the chain 134 through power means controlled by the clutch 148 (Figs. 1 and 3), and the arrangement being such that driving movement of the rolls 2 and 4 starts just prior to the engagement of the work by the buffing roll 14. It will be observed that the piece of leather undergoing buffing operations is fed into the machine progressively during buffing of successive portions of the leather. When approximately one-half of the leather has been buffed the operator releases the treadle

which is immediately followed by movement of the work supporting rolls 2 and 4 away from the buffing roll 14 to an open position where the leather may be readily reversed and reintroduced to obtain treatment of the untreated portion 5 thereof. Then the operations mentioned above are repeated to complete the treatment of the work piece.

Having described our invention, what we claim as new and desire to secure by Letters Patent of 10 the United States is:

1. In a buffing machine, a driven cylindrical roll having an abrasive surface to effect buffing of a surface of a piece of leather, a suction device having an opening adjacent to the abrasive surface of the cylindrical roll to carry away dust-laden air, and a brush roll located in front of the opening into said suction device and in position to brush lightly the surface of the abrasive roll, said brush roll having its bristles in rows alternating with relatively wide spaces between the rows whereby at regular intervals during rotation of the brush roll dust-laden air may enter by way of said spaces into the suction means.

2. In a buffing machine, a driven cylindrical roll having an abrasive surface to effect buffing of a surface of a piece of leather, a suction device having an opening adjacent to the abrasive surface of said roll to carry away dust-laden air, and a brush roll rotated in a direction the same 25 as that of the abrasive roll, whereby adjacent surfaces of the two rolls move in opposite directions, the brush roll having its bristles in rows spaced substantially from each other, said brush roll being of a diameter substantially greater 30 than the corresponding dimension of said opening into the suction device and being located in front of said opening and adjacent to the abrasive surface of the cylindrical roll, each moving row of bristles having an edge which moves 35 in a direction to wipe the leather from the abrasive surface of the cylindrical roll and the spaces between the rows of bristles serving at regular intervals during rotation of the brush roll to permit free access of dust-laden air to the open- 40 ing into said suction means.

3. In a buffing machine, a cylindrical roll having an abrasive surface to effect buffing of a surface of a piece of leather, a suction device having an opening adjacent to the abrasive surface of the cylindrical roll to carry away dust-laden air, and a driven brush roll having its bristles in straight rows parallel to the axis of the brush roll and spaced substantially from each other, said brush roll being of a diameter sub- 50 substantially double the corresponding dimension of said opening into the suction device and being located in front of said opening and adjacent to the abrasive surface of the cylindrical roll, each moving row of bristles having a straight 55 edge which serves to wipe the leather from the abrasive surface of the cylindrical roll and the spaces between the rows of bristles serving at regular intervals to permit free access of dust-laden air to the opening into said suction means.

4. In a buffing machine, a buffing roll, a work supporting roll, a member movable about a horizontal axis to carry the work supporting roll in directions toward and from the buffing roll, power means to drive the work supporting roll 70 whereby it feeds the work while at the same time supporting it against the thrust of the buffing roll, said power means comprising a clutch, and a treadle mechanism connected to the lower end of said member and to said clutch and operable 75

- to cause said member to move the work supporting roll into operative relation to the buffing roll and to control the clutch to initiate operation of the driving means for said work supporting roll.
5. In a buffing machine, a buffing roll, a work supporting roll, a member movable about a horizontal axis to carry the work supporting roll in directions toward and from the buffing roll, means to drive the work supporting roll, said means comprising a clutch, and a treadle mechanism connected to operate said member thereby to move the work supporting roll between work receiving and work presenting positions, said treadle mechanism also having connections to control the clutch in such timed relation to the movement of the work supporting roll that the driving means for the work supporting roll becomes operative just before said roll moves into position to present the work piece to the buffing roll.
10. 6. In a buffing machine, a buffing roll, a work supporting roll having a sprocket wheel secured thereto, a member movable about a horizontal axis to carry the work supporting roll in directions toward and from the buffing roll, said axis being about midway of the length of said member, an idler sprocket mounted adjacent to the lower end of said member, a chain engaging said sprocket and sprocket wheel, power means to drive the chain whereby the work supporting roll feeds a work piece while at the same time supporting it against the thrust of the buffing roll, said power means comprising a clutch, and a treadle mechanism connected to said member and to said clutch to cause said member to move the work supporting roll into operative relation to the buffing roll and to operate the clutch to initiate rotation of the work supporting roll just before the latter presents the work piece to the buffing roll.
15. 7. In a buffing machine, a buffing roll, a work supporting roll having a sprocket wheel secured thereto, a member movable about a horizontal axis to carry the work supporting roll in directions toward and from the buffing roll, idler sprockets mounted on the machine frame adjacent the lower end of said member, a chain engaging said sprockets and sprocket wheel, power means to drive the chain whereby the work supporting roll feeds the work while at the same time supporting it against the thrust of the buffing roll, said power means comprising a clutch, and a treadle mechanism connected to the lower end of said member and to said clutch and operable to cause said member to move the work supporting roll into operative relation to the buffing roll and to operate the clutch to initiate operation of the driving means for the chain-driven work supporting roll.
20. 8. In a buffing machine, a buffing roll, a pair of work supporting rolls one of which is movable to a position to back a work piece during treatment thereof by the buffing roll, said work supporting rolls having sprocket wheels secured thereto, a member movable about a horizontal axis to carry the work supporting rolls in directions toward and from the buffing roll, idler sprockets mounted on the machine frame adjacent to and on each side of the lower end of said member, a chain engaging said sprockets and sprocket wheel, power means to drive the chain whereby the work supporting rolls feed the work while at the same time one of them supports it against the thrust of the buffing roll, said power means comprising a clutch, and a treadle mechanism connected to the lower end of said member and to said clutch and operable to cause said member to move said one of the work supporting rolls into direct co-operative relation to the buffing roll and to operate the clutch to initiate operation of the chain driving means for said work supporting rolls.
